WASHING MACHINE TUB HOLDER

Application filed September 20, 1928. Serial No. 307,259.

Our invention relates to improvements in means for supporting tubs in washing machines; and the primary object of our invention is to produce comparatively simple and inexpensive, yet strong and durable, means of this character, which constitute a support for the tub, and may serve as an oscillator for the same, and a pivotal connection that permits said tub to be tilted, and when tilted to be disengaged entirely from the supporting members, thus rendering it easy and convenient for the operator to empty the tub, and to remove the tub altogether should occasion require.

Heretofore it has been necessary, whenever a washing-machine tub was emptied, either to dip or siphon the water out of the same, or to lift the tub with the water therein bodily off of its support and then empty out the water, the first of which procedures is tedious and time consuming, and the second laborious and requiring the expenditure of considerable strength. With our holder it is a very simple, easy, and convenient matter to tilt the tub into a position which enables all of the water therein to run out, and to lift the tub clear of the machine and take it away, if it be desired to do so for any purpose, also, in the last event, to return the tub to place with the pivotal connection between it and the support restored, and to rock the tub from tilted position back into horizontal and normal position.

Another object is to provide a holder for a tub which at no point penetrates the tub or extends into the interior or above the floor thereof, but, nevertheless, has a connection of such a nature that said holder may serve as the direct oscillating medium for the tub.

Other objects and advantages will appear in the course of the following description.

We attain the objects and secure the advantages of our invention by the means illustrated in the accompanying drawings, in which—

Figure 1 is a side elevation of a practical

form of our washing-machine tub holder, showing the same in connection with parts of a washing machine, including the tub; Fig. 2, an enlarged, vertical section through one of the gravity supports of said holder for said tub, taken generally on lines 2—2, looking in the direction of the associated arrow, in Fig. 5; Fig. 3, an enlarged, bottom plan of the pivotal connection between said holder and said tub, which connection is also gravity support of the holder for the tub; Fig. 4, an enlarged, vertical section through said connection, taken generally on lines 4—4, looking in the direction of the associated arrow, in Fig. 5; Fig. 5, a bottom plan of the holder and tub; Fig. 6, an elevation generally similar to the elevation in the first view, except that herein there is an oscillatory dolly in a stationary tub, and, Fig. 7, a bottom plan and horizontal section on lines 7—7, in Fig. 6.

Similar reference characters designate similar parts throughout the several views.

In the first view parts of the transmission case and of the tub are broken away and in section, and said tub is shown by broken lines in tilted position, the full line position representing the tub completely in place and supported on all three of the holder arms, and the same is generally true of Fig. 6.

In each of Figs. 1 and 6 is represented at 1 a transmission case mounted on wheels 3—3 and a foot 5. Journaled in the cases 1 in the first and second examples are drive shafts 6 and 6', respectively.

Reference will be had first to Figs. 1 to 5, inclusive. A tub is represented at 70 which tub has an imperforate bottom 8, and is provided on one side near the top with a handle 9. Preferably the bottom 8 is set a short distance above the under edge of the wall of the tub 70, and in the present example the outer edge or rim of said bottom is turned down to form a vertical flange 10 which is soldered or otherwise secured to the tub wall. The wall of the tub is beaded just above the bot-

tom 8 to strengthen said wall and assist in securing said bottom in place and supporting the wall thereon, and similarly beaded near the top for strengthening purposes, the 5 beads being indicated by the numeral 11.

Secured to the tub bottom 8 on the under side thereof are two members having concavities therein to form sockets 12, and a bracket 13. The bracket 13 has therein a central opening 14, two end extensions or flanges 15 which fit against and are soldered or otherwise secured to the under-side of the bottom 8, and a bifurcated locking lug 16. The lug 16 extends downwardly from the 10 inner edge of the bracket 13 and curves forwardly or outwardly, as best shown in Fig. 4, and the bifurcation of said lug consists of a central slot 17 which extends from a point a short distance below the top of the 15 lug downwardly to open at the bottom through the bottom of said lug. The outer side of the bracket 13 consists of a lip 18 that is soldered or otherwise secured to the bottom flange 10, and said bracket also has 20 vertical end pieces 19—19 thickened, as represented at 20—20, to form bearings or supports for a horizontal pivot pin 21. The pin 21 has its terminals received and fixed in openings in the bearings 20.

30 Although the brackets 13, with its pin 21, and the sockets 12 are rigidly secured to the tub 70, said bracket and sockets are parts of the holder as a whole.

35 A center piece or hub 22, from which radiate three arms, is pinned at 23 to the shaft 6. One of the aforesaid arms, that indicated by the numeral 24, extends outwardly from the hub 22 at right-angles to the vertical, central, longitudinal plane of the machine, and the 40 other two of the aforesaid arms extend obliquely from said hub, each of said last-named arms being indicated by the numeral 25. Each arm 25 is provided at the outer end with a lug 26, which lug has a convex top 45 receivable in the recess in one of the sockets 12, the distance between the axial center of the hub and the axial center of said lug being equal to the distance between the axial center of the bottom 8 and the axial center 50 of said socket.

55 At the outer end of the arm 24 is a cross-head 27 in and opening through the top and ends of which is a longitudinal slot 28 to receive and support in the bottom thereof the pin 21, the distance between the axis of the hub 22 and the center of the axis of the curved bottom of the cross-head slot 28 is equal to the distance between the axial center of the bottom 8 and the center of the pin axis. 60 That portion of the arm 24 which is directly behind the cross-head 28 is receivable in the slot 17 in the locking lug 16.

65 The tub 70 is mounted on and connected with or attached to the support, consisting of the hub 22 and the arms 24 and 25, by holding

70 the tub in tilted position, substantially as shown by broken lines in Fig. 1, introducing the pin 21 into the cross-head slot 28 from above, and rocking said tub upwardly, over, and downwardly until it comes to rest with the sockets 12 on the lugs 26, said tub then being located with the bottom in a horizontal position. As the tub 70 is rocked over onto the lugs 26, the pin 21 partially rotating in the cross-head 27, the arm 24 is received in 75 the slot 17, and the locking lug 16 is carried downwardly and forwardly beneath the terminal portions of said cross-head, and thus secures said pin in the slot 28, prevents the tub from being lifted off of said arm and 80 said pin from being raised out of said slot.

85 Due to the pivotal connection between the tub 70 and the arm 24, and to the lug and socket connections between said tub and the arms 25, described above, when the hub 22 and said arms are oscillated by the shaft 6, which shaft is the transmission member that oscillates said hub and arms, said tub is similarly oscillated, being partially rotated first in one direction and then in the other by 90 and with said arms.

95 To empty the tub 70 it is simply necessary to grasp the handle 9, which is on the side of the tub opposite to that where the pin 21 is located, tilt said tub over into the position indicated by broken lines in Fig. 1, the tub rocking on and with the pin 21 in the cross-head 27. After being emptied the tub 70 is rocked back again into normal position. Neither of 100 these operations requires the expenditure of a great amount of strength, and each can be easily and quickly performed.

105 As already explained, while the tub 70 is in tilted position, it can be entirely disengaged and removed from the machine by lifting said tub to raise the pin 21 out of the slot 28, the tub being so positioned at this time that the arm 24 is out of the slot 17, and the locking lug 16 is not in position to contact 110 with the cross-head 27 when the tub is raised.

115 It is now seen that the support mounted on the shaft 6, and the associated and connected parts and members on the bottom of the tub 70, carry the latter in normal position, and oscillate the same, enable the tub to 120 be tilted at an angle to enable the contents therein to flow out, and to be rocked back into normal position again, and permit the tub to be removed and replaced provided the same be held in proper tilted position during these 125 operations.

130 The locking lug 16, in addition to the office of preventing removal of the pin 21 from the slot 28, except at such times as such removal is desired, assists the other parts and members in preventing independent rotary motion as between the tub 70 and the support beneath the same, by reason of the fact that the arm 24 is embraced between the sides of the slot 17.

135 If desired, the lugs 26 at the ends of the

arms 25 may be provided with adjusting means, such as vertical bolts 29-29 tapped into and through said lugs from below to receive on their upper ends the sockets 12. The purpose of these bolts is to provide means for adjusting the tub 70, by turning either or both of said bolts up or down as may be necessary, until its bottom is level and its side vertical or exactly erect. These bolts may be omitted, and they are not needed in the second construction or example described below.

In Fig. 6, the tub 70 is stationary, and has therein an oscillating dolly 30 driven from the shaft 6', through the medium of a vertical shaft 31. The dolly 30 has an axial sleeve 32 which is mounted on a vertical bearing sleeve 33 that is secured to the bottom 8 of this tub. The shaft 31 has a collar 34 pinned at 35 thereto below the bearing 33, and said shaft extends upwardly through the bearing 33. The lower terminal of the shaft 31 is angular and tapered, as represented at 36, and adapted to fit into an angular and tapered socket in the top of the shaft 6'. Secured to the top of the shaft 31 above the bearing 33 is an angular collar 37 that engages an angular part of the sleeve 32 above said bearing. The collar 37 is held in place on the shaft 31 and the top of the bearing 33 by means of a nut 38 screwed onto the upper terminal of said shaft.

The oscillating shaft 6' drives the shaft 31, through the medium of the angular terminal 36, and said shaft drives the sleeve 32 and the dolly 30, through the medium of the angular collar 37. With the exception of the angular and tapered terminal 36 at the bottom of the shaft 31, these parts are old and well known.

Here the tub support has, in place of the oscillatory hub 22, a fixed hub 39 which is mounted on and rigidly connected with the transmission case 1 below. The shaft 6' extends upwardly through the hub 39 and oscillates therein. In other respects the two supports are similar.

The tilting and the removal and replacing of the tubs are accomplished in practically the same manner in both examples, but, when the tub in the second example is tilted, the bottom of the shaft 31 tips out of the socket in the shaft 6', and, when said tub is rocked or swung over into normal position, said terminal reenters said socket, thus reestablishing the driving connection for the dolly.

The arm 24 in the second case necessarily extends out over one side of the machine, otherwise the tub could not be tilted to a sufficient degree, and, at such times as the first tub is to be tilted, the corresponding arm in the first case must be similarly positioned.

The socket in the top of the shaft 6', for the shaft terminal 36, is designated by the numeral 40.

Except in the particulars pointed out, the

two machines illustrated in connection herewith are generally and specifically similar, as may be inferred from previously contained statements.

More or less change in the shape, size, construction, and arrangement of some or all of the parts of this holder, in addition to those hereinbefore specifically pointed out, may be made, without departing from the spirit of our invention, or exceeding the scope of what is claimed.

We claim:

1. The combination in a washing machine of an oscillatable shaft, a tub and a holder therefor comprising, a tub support provided with outwardly extending arms, the said tub being supported on said arms and a pivotal connection between a side of said tub and one of said arms whereby the tub may be tilted with respect to said support and oscillated therewith.

2. The combination in a washing machine of an oscillatable shaft, a tub and a holder therefor comprising, a support, having arms extending radially therefrom, the said tub being normally supported on said arms in a concentric relation with respect to said shaft and pivotal connections between one of said arms and said tub whereby the tub may be oscillated by said support and tilted to an angular relation with respect thereto.

3. A washing machine comprising in combination, a transmission case provided with a bearing hub, an oscillatable drive shaft in said hub provided with a socket in the upper end thereof, supporting arms extending from said hub, a tub resting on said arms when in an upright position, pivotal connections between said tub and one of said arms whereby it may be swung from said upright position to a tilting position, a rotatable member in said tub provided with a portion detachably engaging the socket of the drive shaft when the tub is in upright position whereby said member may be driven.

4. The combination, in a washing-machine tub and holder, of a center piece and radial arms connected therewith, one of said arms having a cross-head in which is a slot, and the others of said arms having supporting parts, of a tub provided on the bottom with a pivot pin receivable in said slot, and with parts to engage said supporting parts.

5. The combination, in a washing-machine tub and holder, with a center piece and arms connected therewith, one of said arms having a cross-head in which is a slot, and the others of said arms having supporting parts, of a tub provided on the bottom with a pivot pin receivable in said slot, with a locking lug to retain said pin in said slot when the tub and support are in a certain relative position.

6. The combination, in a washing-machine tub and holder, with a center piece, and arms connected therewith, one of said arms having

a cross-head with a slot therein, and the others of said arms having supporting parts, of a tub provided on the bottom with parts to engage said supporting parts, and a bracket secured to the bottom of said tub, having a locking lug bifurcated to receive said first-named arm, and provided with a pin receivable in said slot, said lug extending downwardly and partly around said cross-head and being adapted to engage said cross-head and prevent the tub from being lifted to raise said pin out of said slot except when said tub is tilted.
